UNITED STATES PATENT OFFICE

JOHN McCOY, OF VIENNA CROSS ROADS, OHIO.

SCREW-DRIVER.

No. 873,771.

Specification of Letters Patent.

Patented Dec. 17, 1907.

Application filed January 7, 1907. Serial No. 361,051.

To all whom it may concern:

Be it known that I, JOHN McCOY, a citizen of the United States, residing at Vienna Cross Roads, in the county of Clark and State of Ohio, have invented certain new and useful Improvements in Screw-Drivers, of which the following is a specification, reference being had therein to the accompanying drawings.

10 The present invention relates to screw-drivers, and more particularly to that class of instruments known as bench screw-drivers which are adapted to be supported on an adjustable bracket above a work bench and are 15 adapted to be moved to any desired position above the bench to set a screw in any part of the work carried by the bench.

The object of the present invention is to provide an instrument of this character in 20 which the screws can be inserted in any suitable manner and will be supported and set without other manipulation by the operator than the operation of the screw-driver; and to provide an improved screw holder for supporting the screw while it is being driven; and further to provide an improved frame for supporting the screw-driver proper; and to provide the device with means for drilling the work to form apertures in which to start 30 the screws.

With these objects in view my invention consists in certain novel features of construction hereinafter to be described, and then more fully pointed out in the claims.

35 In the accompanying drawings, Figure 1 is a side elevation of a device embodying my invention; Fig. 2 is a detail view of the screw holder; and Fig. 3 is a detail view of the handle on the screw-driver shaft and the 40 drill-chuck mounted on the same.

In these drawings, in which I have illustrated the preferred form of my device, the reference numeral 1 indicates the supporting frame which is preferably of cast metal 45 and substantially U-shaped. This frame is provided at its rear with a suitable swiveled connection 2 for connecting the same with the supporting bracket, which forms no part of the present invention and is not here 50 shown. The ends of the U-shaped portion are provided with bearings 3 in which is mounted a shaft 4 which has both a rotatory and a reciprocatory movement relatively to 55 said supporting frame. The shaft 4 is provided between the arms of the U-shaped frame with oppositely facing bevel pinions,

one of which, 5, is splined or otherwise secured to the shaft 4 in such a manner as to allow the shaft to reciprocate therein, but to cause the same to rotate in unison therewith, 60 the other of the said pinions, 5^a, being loosely mounted on said shaft to allow said shaft both a rotatory and a reciprocatory movement independent of said pinion. Suitable sleeves 6 are mounted upon the shaft 4 65 and extend between the pinions 5 and 5^a and the arm 7 forming part of the frame 1 and provided with an aperture through which the shaft 4 extends. These sleeves serve to hold the pinions 5 and 5^a in their proper positions against the bearings 3 of the frame and to permit the shaft to reciprocate therein. 70

The member or arm 7 of the frame 1 is preferably cast integral therewith, and, as stated, is provided near its outer end with an 75 aperture through which the shaft 4 passes and has its outer end turned down or otherwise provided with a stud-shaft 8 upon which is mounted a bevel gear 9 adapted to mesh with the bevel pinions 5 and 5^a on the 80 shaft 4, the pinion 5 serving to drive the shaft 4, while the pinion 5^a serves merely as a guide for the opposite side of the bevel gear 9 to hold the same in proper engagement with the driving pinion 5. The bevel gear 9 is 85 provided with a suitable handle 10 for rotating the same. This handle may be secured to the pinion in any desired manner, but I prefer to mount the handle 10 upon the outer end of the shaft 8 and connect the same with 90 the gear 9 by a suitable ratchet mechanism, here shown as inclosed in a casing 11, which is preferably of the reversible type, whereby the direction of movement of the handle 10 may be reversed and the shaft 4 driven in the 95 opposite direction.

The lower end of the shaft 4 which extends below the lower arm of the bracket 1 is provided with a suitable screw-driver 12, while that portion of the shaft which extends 100 above the upper arm of the U-shaped bracket 1 is provided with a handle 13 loosely mounted thereon but held against longitudinal movement thereon. A spring 14 is coiled about the shaft 4 between the 105 lower side of the handle 13 and the upper bearing 3 and serves to hold the shaft 4 normally in its elevated position, but to permit the same to be moved downward when pressure is exerted upon the handle 13 to cause 110 the screw-driver to follow the screw as it is set into the wood.

The shaft 4 is preferably extended beyond the handle 13 and the projecting end thereof is provided with a screw thread, as shown at 15, adapted to receive a tool chuck 16 which 5 may be provided with a suitable drill or bit 17 for boring the wood to provide an aperture in which to start the screws.

The lower arm of the U-shaped bracket 1 is provided with a tube 18 which surrounds 10 the lower end of the shaft 4 and the screw-driver carried thereby and is secured in any suitable manner to the lower bearing 3. The tube 18 is provided with a feed conduit 19 extending at an angle thereto and preferably 15 having its mouth flared, as shown at 20. Secured to the lower end of the tube 18 is a screw holder 21, preferably having its upper end provided with an internal screw thread 22, by means of which it is secured to the 20 tube 18. This screw holder preferably consists of a cylindrical casing 23, in the upper end of which the screw thread 22 is formed, the lower end being provided with jaws 24 having their inner faces beveled, as shown at 25, and provided with an aperture 26 at the lower edge thereof. These jaws are preferably two in number and are formed substantially semi-circular. Springs 27 are secured at their upper ends to the casing 23, as shown 30 at 28, and at their lower ends to the jaws 24 and serve to hold the jaws normally in their closed position.

In order to adapt the screw holder 21 to hold screws of various sizes, the same is provided with an internal guide 29 which is preferably in the form of a cylindrical tube fitting within the casing 23 and provided with a shoulder at its upper end, as shown at 30, which is adapted to engage a corresponding 40 shoulder 31 formed near the base of the screw-threaded portion 22 of the casing 23, thereby supporting the guide 29 in its proper position in the casing 23. These guides are readily removable and are made with the internal bore of different sizes to correspond to 45 the diameters of the heads of the several standard sizes of screws, and, by simply removing one guide and inserting another, the holder can be adapted to receive any of the 50 standard sizes of screws and to hold the same in a vertical position while it is being set into the wood. The guides 29 are preferably formed all of one size having their lower ends tapered, as shown at 33, and are then bored 55 centrally to provide the same with an internal aperture of the proper diameter. This boring of the guide 29 cuts away a portion of the tapered lower end thereof corresponding to the diameter of the bore and causes the 60 lower edge of the same to be substantially flush with the beveled inner face of the jaws 24 so that the face 25 of the jaw practically forms a continuation of the guide 29 and the screw head is at all times in contact with the 65 guiding surface.

The operation of the device will be readily understood from the foregoing description. The screw is fed into the conduit 19 either by hand or in any suitable manner and falls by gravity through the lower end of the tube 70 18 into the holder 21 which has been provided with a tubular guide 29 having a central bore corresponding to the diameter of the head of the screw. Thus as the screw drops into said guide and its point moves 75 into engagement with the aperture 26 in the lower end of the jaws 24, the screw is held in a substantially vertical position. The handle 13 is then depressed against the tension of the spring 14 to move the screw-driver 12 80 into engagement with the slotted head of the screw. The handle 10 is then operated to rotate the screw-driver and the screw is set into the wood, continual pressure being exerted upon the handle 13 to hold the screw-driver continually in engagement with the slotted head of the screw. As the screw moves downward the jaws 24 separate against the tension of the springs 27 and allow the head of the screw to pass through 85 the same. After the screw has been fully set the pressure is removed from the handle 13 and the spring 14 immediately moves the shaft 4 to its elevated position and retains the parts in their normal position. When 90 it is desired to set screws in hard wood, it is desirable to bore the wood to provide the same with an aperture in which to start the screw. In order to accomplish this as readily as possible I have provided the end 100 of the shaft 4 opposite that end which carries the screw-driver 12 with a chuck 16 which may be provided with a bit or drill 17 of a proper size to provide an aperture for the screw which is to be set. The frame 1 being 105 provided with a swiveled connection 2 can be readily inverted to bring the bit 17 into operative relation with the work. The swiveled connection 2, upon which the device is mounted, is preferably placed midway of the bit 17 and the tool holder 21 so that the inversion of the frame 1 will bring either the bit 17 or the screw holder 21 into proper relation with the work without further adjustment of the supporting means. 110

I wish it to be understood that I do not desire to be limited to the exact details of construction shown and described, for obvious modifications will occur to a person skilled in the art.

Having thus fully described my invention, what I claim as new and desire to secure by Letters Patent, is:—

1. In a device of the character described, the combination, with a substantially U-shaped frame, an apertured member carried thereby between the arms of said U-shaped frame and extending substantially parallel with said arms, a shaft mounted in said arms and extending through said apertured mem- 125 130

ber and having both a rotatory and a reciprocatory movement relatively to said frame, a bevel pinion mounted on said shaft to cause said shaft to rotate therewith and to permit 5 the same to reciprocate independently thereof, a bevel gear mounted on said apertured member beyond said shaft and adapted to mesh with said bevel pinion, means for rotating said bevel gear, and a screw-driver bit carried by the lower end of said shaft, of 10 a screw holder supported from said frame and adapted to receive said bit.

2. In a device of the character described, 15 the combination, with a frame, a shaft mounted on said frame and having both ends extending beyond the same, means for imparting a rotatory movement to said shaft, a handle mounted on one end of said shaft to move the same longitudinally of said frame, 20 a drill-chuck mounted on said shaft beyond

said handle, a screw-driver bit mounted on the other end of said shaft, and a swiveled connection for securing said frame to a support, of a screw holder carried by said frame and adapted to receive said screw-driver bit. 25

3. In a device of the character described, the combination, with a frame and a screw-driver, of a screw holder comprising a casing, spring-pressed jaws mounted beneath said casing and having their inner faces beveled, 30 a removable guide mounted within said casing and having its lower end tapered to correspond with the beveled inner faces of said jaws, substantially as described.

In testimony whereof, I affix my signature 35 in presence of two witnesses.

JOHN McCOY.
